UNITED STATES PATENT OFFICE.

JAMES K. P. PINE, OF TROY, NEW YORK, ASSIGNOR TO UNITED SHIRT AND COLLAR COMPANY, OF TROY, NEW YORK, A CORPORATION OF NEW YORK.

COLLAR.

No. 882,415.

Specification of Letters Patent. Patented March 17, 1908.

Application filed July 2, 1904. Serial No. 215,062.

To all whom it may concern:

Be it known that I, JAMES K. P. PINE, a citizen of the United States of America, and resident of Troy, county of Rensselaer, State 5 of New York, have invented certain new and useful Improvements in Collars, of which the following is a specification, reference being had to the accompanying drawings, forming a part thereof.

10 My invention relates to improvements in collars, and particularly to the class of collars known as upright turn-down collars. In collars of this description it has been common in the past to make one end of the neck 15 band extend beyond the end of the body of the collar, the said end being adapted to overlap the opposite end of the neck band, and to be received between the neck band and the body or turn-down portion of the collar. 20 This end is intended to serve as a locking piece, to retain the various parts of the collar in their proper relative positions when worn. One great drawback to the use of collars of 25 this description has been the difficulty experienced in adjusting the cravat therein when in place upon the wearer, and this difficulty has been much aggravated by the form and construction of the extended portion of the neck band.

30 So far as I am aware, all collars employing the lock-front have the upper end edge of the extended portion of the neck band rounded. I have discovered that this rounded portion of the neck band has served as a guide to 35 guide a portion of the cravat up to the bight of the collar, whereby the cravat has become firmly jammed or caught between the upper edge of the extended portion of the band and the bight formed at the folded over portion 40 of the collar, to the great discomfort of the wearer.

It is one of the objects of my present invention to overcome this difficulty, and I attain this object by making the upper and 45 outer edges of the extended portion of the collar substantially square, causing them to terminate in a sharp corner. The wedge-shaped opening guiding the cravat up into the bight of the collar is thus done away with, 50 and the tendency of the cravat to jam at this point obviated. Moreover, it will be well understood that the neck band of a collar so constructed will be more securely held in position when adjusted on the person of the 55 wearer, than will a collar having the upper

edge of this portion of the neck rounded, because the sharp corner will be pressed firmly up into the bight of the collar and a more positive and absolute "lock-front" will result. A further source of annoyance with a 60 collar of this description has been that the lower edge of the extended portion of the neck band has been apt to protrude below the lower edge of the turn-down portion of the collar, due to the spreading of the collar, 65 which sometimes occurs, especially when worn with a shirt having a low cut front. To prevent any possibility of such unsightly appearance, I have, in accordance with my present invention, rounded the lower edge of 70 the extended portion of the neck band, so that no matter how much the collar spreads, the lower edge of the neck band can never protrude below the lower edge of the turn-down portion of the collar.

75 I will now proceed to describe in detail a collar embodying my invention, and will then point out the novel features in claims:

In the drawings—Figure 1 is a view in perspective of a collar embodying my invention, 80 the two ends being brought together to a position occupied when the collar is worn. Fig. 2 is a view in front elevation of a collar with the ends thereof separated. Fig. 3 is a fragmentary view of the front portion of the 85 collar, showing the ends adjusted to the position shown in Fig. 1, but with portions of the body of the collar broken away, in order to better illustrate the relative position of the neck band parts. Fig. 4 is a view in trans- 90 verse section showing the extended end of the neck band of the collar engaged between the neck band and turned-over portion of the other end of the collar. Fig. 5 is a view showing the collar in a "spread" condition. 95

The collar illustrated comprises a neck band 1 and a turn-down or body portion 2. The neck band is provided with the usual buttonholes for receiving studs or collar buttons for adjusting the collar in position. 100 One end of the neck band 1 is extended beyond the body portion, forming a tab 3, which is adapted to fit, and be received between, the neck band and body portion of the collar at the other end thereof. This tab 105 or extension has an upper curved edge 4 terminating in a sharp corner 5. When the collar is worn, the edge 4 substantially fits the bight or fold line of the collar, and the sharp corner 5 pressed upward therein, insures the 110

complete locking of the parts. The angle formed by the lines bounding the upper edge 4 and the end edge 6 of the tab or extension 3, is substantially a right angle, so that there will be no tendency for the cravat to be drawn up into the bight of the collar by engagement with the tab or extension 3.

The lower end portion of the tab or extension 3 is cut away or rounded, as shown at 7 in the drawings, and by so cutting away and rounding this lower edge, I prevent the possibility of exposure of the tab when the collar spreads. Fig. 5 of the drawings shows a collar badly spread, but it will be seen that the 15 collar tab (shown complete in dotted lines) is in no way exposed below the body portion of the collar, and the unsightly effect, common under such circumstances, is thus avoided.

20 What I claim is:

1. A turn-down collar of the character specified, having one end of its neck band extended beyond the end of the body of the collar and adapted to fit into the folded portion of the other end of the collar, the upper 25 edge of the said extended portion terminating in substantially a sharp corner.

2. A collar of the type specified, having a neck band and a folded over body portion, 30 the neck band extending beyond the body

portion at one end of the collar and adapted to fit into the folded over portion of the other end of the collar, the upper and end edges of the neck band terminating and uniting in a substantially right angled corner. 35

3. A collar of the type specified, having a neck band and a folded over body portion, the neck band having a tab or extension projecting beyond the body portion at one end of the collar and adapted to fit into the folded over portion of the other end of the collar, said tab or extension having an upper sharp corner and a lower rounded corner substantially as and for the purpose specified. 40

4. A turn-down collar of the character 45 specified, having one end of its neck band extended beyond the end of the body of the collar and adapted to fit into the folded portion of the other end of the collar, the upper edge of the said extended portion terminating in substantially a sharp corner, and the lower edge thereof rounded and cut away sufficiently to prevent exposure thereof below the lower line of the body of the collar, should the collar spread. 50
